(57) **CLAIM**

The ornamental design for a medical dressing, as shown and described.

DESCRIPTION

FIG. 1 is a perspective view the new design for a medical dressing;

FIG. 2 is a top view thereof;

FIG. 3 is a bottom view thereof;

FIG. 4 is a front side view thereof;

FIG. 5 is a rear view thereof;

FIG. 6 is a right side view thereof, the left side view being a mirror image thereof; and,

FIG. 7 is a perspective view showing the bottom layer of the medical dressing folded open.

The surface shading illustrated in the drawings is provided merely to highlight the contour of design; it is not intended to be illustrative of texture or gloss.
